E. S. GIBSON

CONTROLLING MECHANISM

Filed Sept. 20, 1923

Inventor
Earl S. Gibson,
By R. Chapman Atty.

UNITED STATES PATENT OFFICE.

EARL S. GIBSON, OF RIDGEWOOD, NEW JERSEY, ASSIGNOR TO WESTERN ELECTRIC COMPANY, INCORPORATED, OF NEW YORK, N. Y., A CORPORATION OF NEW YORK.

CONTROLLING MECHANISM.

Application filed September 20, 1923. Serial No. 663,747.

To all whom it may concern:

Be it known that I, EARL S. GIBSON, a citizen of the United States, residing at Ridgewood, in the county of Bergen, State 5 of New Jersey, have invented certain new and useful Improvements in Controlling Mechanism, of which the following is a full, clear, concise, and exact description.

This invention relates to circuit controlling mechanism, and particularly to such devices when applied to telephone exchange systems employing machine switches for extending connections.

An object of the invention is an improved 15 method of rendering groups of trunks non-selectable to automatic switches under the control of operators.

A feature of the invention is the provision, in a system where selective switches 20 extend connections over trunks to operators' positions, of a multi-contact relay device controlled by the operator for rendering a group of said trunks non-selectable to the switches.

25 A further feature relates to the provision of means whereby the trunks are rendered non-selectable to the switches only at such times as the switches are attempting to make connections to said trunks.

30 Such other and further features as are contemplated by this invention will become more fully understood from the following detailed description and also from the annexed claims.

35 Referring to the drawing, there is shown a portion of an automatic selective switch 100 constructed and arranged to operate on the coordinate principle. This switch consists of a plurality of horizontal link

40 circuits 108, 109, 110, 111 and 112, which serve to interconnect incoming trunks and outgoing trunks. A plurality of incoming trunks, of which two, 104 and 105, are illus- 45 trated, terminate in the switch in vertical rows of contacts, such as rows 114 and 113. Each trunk in turn is arranged to make connection with any one of the horizontal links. The switch also contains a plurality of vertical rows of outgoing trunks, two of

50 which, 115 and 116, are shown. The row 115 includes a group of trunks 106, which lead to a distant manual office and appear at an operator's position 132. The row 116 likewise includes another group of trunks

107 outgoing to a distant manual office and 55 appearing at the operator's position 133. It will be noted that each of the outgoing trunks has but a single appearance in the coordinate switch 100. In other words, each 60 trunk has access to only one of the horizontal link circuits. A convenient manner of dividing the outgoing trunks into numerical groups for selective purposes is to assign each group to either a whole or a portion of 65 a vertical row of contacts in the switch 100. 65

For operating the selective switch 100 there are provided a plurality of vertical operating rods, one for each vertical row of contacts, and which are actuated by means 70 of vertical magnets 117, 118, 119, 120. Furthermore, there are provided a plurality of horizontal operating rods, one for each of the horizontal link circuits and arranged to be actuated respectively by means of the operating magnets 121, 122, 123, etc. 75

For a more detailed description of the construction and operation of a switch of this character, reference is made to the patent to S. B. Williams, No. 1,517,331, granted December 2, 1924. 80

For controlling the selective operation of the switch 100 there is provided a marking and controlling mechanism 101. The controlling mechanism 101 is arranged to be associated with the various groups 85 of trunks 106, 107, etc. by means of a multi-contact relay connecting device 102. The device 102 consists of a plurality of multi-contact relays 140, 141 and 142, each of which is individual to a separate group 90 of trunks. When one of these relays is operated it associates the relays 136, 137, 138, 139, etc. with the respective trunks of the corresponding group.

It frequently happens that the operator at 95 the distant manual office wishes to leave her position or for some other reason it becomes desirable to cause a cessation of traffic over the trunks leading to such position. To accomplish this the operator is provided with 100 a make busy key, which when operated renders the associated group of trunks non-selectable to the switches of the distant mechanical office. For instance, the operator's position 132 at which the group of trunks 106 terminates is equipped with the key 134, while the operator's position 133 is equipped 105 with the key 135 for the purpose of render-

ing non-selectable trunks 107. These keys when manipulated render a multi-contact relay device effective to apply busy conditions to the sleeve conductors of all trunks 5 in the group concerned.

Assume, for example, that the operator at position 132 desires to render the group of trunks 106 including trunks 124, 125 and 127 non-selectable to the switch 100 and to other 10 switches in which these trunks may appear. To do this she depresses the make busy key 134. Key 134 places ground on the cable conductor 149, causing the operation of the relay 144 at the distant mechanical office.

15 The next time a call is extended over one of the incoming trunks 104, 105, etc., and intended for one of the outgoing trunks in group 106, relay 144 being energized, causes the operation of the multi-contact relay 147 20 individual to the group of trunks 106. Since a call has been extended to the switch 100, a relay 141 is operated for the purpose of associating the controlling mechanism 101 with the switch 100 and with the trunks 106 25 for the purpose of testing the same. When relay 141 operates, a circuit is closed from battery through the winding of multi-contact relay 147, contact of relay 144, conductor 150, contact of relay 141 to ground. Relay 147 then operates and through its contacts extends ground potential over the conductors 151, 152, 153 and 154, to the sleeve conductors of the respective trunks 124, 125, 126 and 127 of the group 106. Since the 30 test conductors of the several trunks are grounded, the respective test relays 136, 137, 138 and 139 in the controlling device will be energized to indicate to such device that all trunks in the tested group are busy and no 35 connection can be extended over the trunk group 106. The circuit for the relay 136 may be traced from battery through the right hand winding of said relay, contact of relay 141, conductor 155, to the grounded 40 sleeve conductor of the trunk 124. The circuit for relay 137 may be traced from battery through its right hand winding, contact of relay 141, conductor 156 to the 45 grounded sleeve conductor of the trunk 125. In a similar manner circuits may be traced 50 for the other test relays in the controlling mechanism.

In the manner above explained, an artificial busy condition is placed upon the group 55 of trunks 106 to render them non-selectable to the switch 100 during the interval in which it is attempting to make connection with one of said trunks. As soon as the 60 controlling mechanism finds that no connection can be extended over the group 106 it may control the selection of a trunk in some other group leading to an answering operator's position. The release of relay 141 65 causes the release of multi-contact relay 147

and the ground potential is removed from the test conductors of respective trunks of the group 106.

Should another call appear on the switch 100 for one of the trunks in group 106, the 70 relay 141 in operating causes relay 147 to operate as long as relay 144 is maintained energized and the artificial busy condition is replaced on the trunks of the group 106 to render them non-selectable to the switch 100. 75 When the operator at position 132 wishes to receive calls over the group 106, she again releases the key 134, causing the release of relay 144.

In a manner similar to that already described, any of the remaining groups of trunks, such as the group 107, may be rendered non-selectable to the switch 100 by the depression of the corresponding key at the operator's position and the operation of 85 the proper relay 143, 145, etc.

For a more complete explanation of the manner in which the switches 100 are operated under the control of the controlling and testing mechanism 101, reference is made to the patent to S. B. Williams, No. 1,517,331, granted December 2, 1924.

What is claimed is:

1. In combination, a group of trunks, an automatic switch for selecting said trunks, a controlling device for controlling the selective operation of said switch, a multi-contact relay having a contact for each of said trunks, manual means, and means controlled jointly by said device and by said manual means for operating said relay to place a busy condition upon each of said trunks. 95

2. In combination, a group of trunks, an automatic switch for extending connections over said trunks, a control device for selectively controlling said switch, said trunks arranged to be selectable by the absence of electrical conditions thereon, a relay device having an individual contact for each of said trunks, manual means, and means controlled jointly by said control device and said manual means for operating said relay device to extend ground potential through said contacts to each of said trunks for rendering the same non-selectable to the switch. 105

3. In combination, a selective switch, a group of trunks appearing in said switch, a controlling device, means for associating said device with said switch for controlling the selective operation thereof to extend a connection over one of said trunks and for thereupon disassociating said device from the switch, and means responsive to said device for rendering said trunks busy during the time said device is associated with the switch. 110

4. In combination, an automatic switch, a control device for selectively controlling said switch, operators' positions, a plurality of groups of trunks extending from said 115 120 125 130

switch to said positions and arranged to be selected by said switch, a plurality of multi-contact relays, one for each group of trunks, each relay having an individual contact for 5 each of the corresponding trunks, keys at the operators' positions, and means controlled jointly by said device and by said keys for selectively operating said relays to apply an electrical condition to each of 10 the corresponding trunks and render the same non-selectable to said switch.

5. In combination, a group of trunks, an automatic switch for selecting said trunks, a controlling mechanism for testing said 15 trunks, a multi-contact relay, means for operating said relay for rendering such trunks non-selectable whenever a test of said trunks is about to be made.

6. In combination, a plurality of groups 20 of trunks, an automatic switch for selecting said trunks, a controlling mechanism for testing any one of said groups, a number of multi-contact relays, one for each group of said trunks, and means for operating one of 25 said relays to render the trunks non-selectable whenever a test of such trunks is about to be made.

7. In combination, a group of trunks, an automatic switch for selecting said trunks, 30 a controlling mechanism for testing such trunks to ascertain an idle one, and means responsive to said testing mechanism when-

ever the same is about to perform a test of such trunks for rendering said trunks busy.

8. In combination, a selective switch, a group of trunks appearing in said switch, a controlling device, means for connecting said device to said switch for controlling the selective operation thereof to extend a connection over an idle one of said trunks and for thereupon disassociating said device from the switch, and means responsive to said device whenever it is about to be connected to said switch for rendering said trunks busy and for maintaining said trunks busy during the time said device remains connected to said switch.

9. In combination, a selective switch, an operator's position, a group of trunks appearing in said switch and leading to said position, a switch controlling and testing device, means for connecting said device to said trunks for the purpose of making a simultaneous test of said trunks to determine an idle one for the establishment of a connection through said switch, and means controlled from the operator's position for placing a busy condition on all of said trunks during the time said testing device is connected thereto.

In witness whereof, I hereunto subscribe my name this 17th day of September A. D., 1923.

EARL S. GIBSON.
